UNITED STATES PATENT OFFICE.

EDWARD B. VANDERGAW, OF BROOKLYN, AND JULES HEINRICH, OF NEW YORK, N. Y.,
ASSIGNORS TO FRED BUTTERFIELD & CO. INC., OF NEW YORK, N. Y., A CORPORA-
TION OF NEW YORK.

DESIGN FOR A FLOCKED VOILE FABRIC.

Application filed July 6, 1923. Serial No. 6,689. Term of patent 3½ years.

To all whom it may concern:

Be it known that we, EDWARD B. VANDERGAW and JULES HEINRICH, citizens of the United States, residing, respectively, in the borough of Brooklyn and the borough of Manhattan, in the city and State of New York, have jointly invented a new, original and ornamental Design for Flocked Voile Fabric, of which the following is a specification, reference being had to the accompanying drawing, forming part hereof.

The figure is a plan view of a piece of flocked voile fabric showing our new design.

We claim:

The ornamental design for flocked voile fabric, as shown.

EDWARD B. VANDERGAW,
JULES HEINRICH.
